UNITED STATES PATENT OFFICE.

H. CLAY PRICE, OF NEW YORK, N. Y., ASSIGNOR TO THE SCOVILL MANUFACTURING COMPANY, OF SAME PLACE.

APPARATUS FOR WASHING PHOTOGRAPHIC PLATES.

SPECIFICATION forming part of Letters Patent No. 354,344, dated December 14, 1886.

Application filed June 8, 1886. Serial No. 204,460. (No model.)

To all whom it may concern:

Be it known that I, HENRY CLAY PRICE, of New York, in the county of New York and State of New York, have invented a certain new and useful Improvement in Apparatus for Washing Photographic Plates, of which the following is a specification.

This improvement relates to an apparatus for which on the 1st day of May, 1883, Letters Patent No. 276,875 were granted to the Scovill Manufacturing Company as my assignee. That apparatus consisted, essentially, of a vessel provided with racks adapted to hold photographic plates at the edges only in an upright position, and a perforated false bottom sustaining the lower edges of the plates, said vessel having pipes for conveying water to it and away from it. One or more of the racks had a connection with the vessel, which permitted of its adjustment into different positions in order that the apparatus might be used for different-sized photographic plates.

My present improvement consists in the combination, in an apparatus for washing photographic plates, of a vessel adapted to contain water, pipes for conveying water to and away from the vessel, and a frame adapted to be inserted into and removed from the vessel, and having a perforated bottom which, when the frame is in place, will be elevated somewhat above the bottom, a space being left between the sides and ends of the frame and the bottom of the frame, and racks for holding photographic plates to be washed. Preferably one or both of the racks will be capable of adjustment, so that photographic plates of different sizes may be held in the frame. The frame may be lifted out of the vessel whenever it is desirable to remove plates from the water in the vessel.

In the accompanying drawings, Figure 1 is a plan of an apparatus embodying my improvement. Fig. 2 is a vertical longitudinal section of the same. Fig. 3 is a perspective view of the frame in which the photographic plates are to be supported, said frame being removed from the vessel.

Similar letters of reference designate corresponding parts in all the figures.

A designates a vessel, shown as of rectan-

gular form, and made preferably of zinc or analogous metal. It is provided with a cover, A', which is hinged in place at one side. As here shown, the cover is provided with a rim which, when the cover is closed, will lap over the upper edge of the body of the vessel.

B designates a pipe leading to the lower part of the vessel for conducting a stream of water thereto, and C designates a pipe extending from the upper part of the vessel, and serving to convey away the water after it has passed through the vessel. The pipe B may be connected to any suitable service-pipe and the pipe C to any waste-water or sewer pipe.

D designates a frame having a perforated bottom plate, d', having the edges bent downward, so as to form supports d''. From the bottom d', near its corners, uprights d'', which may be made of brass or other metal wire, extend. The upper ends of these uprights are connected by intervening portions of wire, forming handles by which the frame may be lifted. Side pieces, d', and end pieces, d'', are connected to the uprights d''. These side pieces and end pieces may be made of a continuous piece of zinc or analogous metal. They are elevated above the bottom d', so that a space is left between the sides and ends and the bottom.

The frame D is of such size that it will fit snugly within the vessel A, the handles being near the top of the vessel when the frame is in place. The bottom of the frame will be above the pipe B. Water can circulate upwardly within the frame from the pipe B. The frame is provided with racks E F, for holding the photographic plates to be washed. The rack E is made by attaching a corrugated strip of zinc or analogous metal to the inner side of one of the end pieces d'' of the frame D. The rack F is made of a plain strip of metal, having attached to one side a corrugated strip of metal. The racks E F may, however, be differently constructed, but must have opposite grooves, b.

The side pieces d' of the frame D are provided with slideways g, into which the rack F may be inserted, so that it and the rack E will be in proper relative positions to support photographic plates of different sizes to be washed. While the photographic plates are

held in the racks they will rest upon the perforated bottom *d* of the frame *D*. The grooves *b* of the racks will hold the photographic plates out of contact with one another.

5 The frame *D* is not fastened within the vessel *A*; consequently it may be removed from the latter and replaced at pleasure.

What I claim as my invention, and desire to secure by Letters Patent, is—

10 In an apparatus for washing photographic plates, the combination of a vessel, pipes for

conveying water to and from the vessel, and a frame fitted within the vessel and consisting of a bottom elevated above the bottom of the vessel and having a space between its bottom and its sides and ends, and racks for holding photographic plates while resting upon the bottom.

H. CLAY PRICE.
